UNITED STATES PATENT OFFICE.

JAMES MACKIRDY, OF NEW YORK, N. Y., ASSIGNOR TO THE MERGENTHALER LINOTYPE COMPANY, OF NEW YORK.

LINOTYPE-MACHINE.

SPECIFICATION forming part of Letters Patent No. 648,829, dated February 13, 1900.

Application filed March 21, 1898. Serial No. 674,603. (No model.)

To all whom it may concern:

Be it known that I, JAMES MACKIRDY, of New York, (Brooklyn,) county of Kings, and State of New York, have invented a new and 5 useful Improvement in Linotype-Machines, of which the following is a specification.

In the Mergenthaler linotype-machine such as represented in Letters Patent of the United States No. 436,532, dated September 16, 1890, 10 the composed line of matrices is shifted horizontally into a grooved or channeled support having a rising-and-falling motion and commonly denominated the "first elevator." The matrix-line is pushed into this elevator 15 from the left and lowered thereby to the mold, after which the elevator rises to a level higher than that at which it received the matrices, and they are pushed out toward the right for transference to the distributing mechanism. 20 As the elevator is open at the right-hand side, it is necessary to provide it with dogs or retaining devices to hold the matrices after their introduction and while the elevator is being lowered and raised, and this in order 25 to prevent the matrices from escaping at the open end. The dogs, pawls, or retaining devices heretofore in use have been of a complicated and delicate character and required to be mechanically operated in order to lock 30 and unlock the end of the matrix-line.

The object of the present invention is to simplify the means for retaining the matrix-line within the elevator, avoid the necessity of coöperating parts, and still admit of the 35 line being shifted right and left into and out of the elevator without difficulty and without injury to the matrix characters.

To this end it consists, broadly, in pawls or dogs applied to the elevator and so formed 40 that they will yield under moderate pressure exerted by the matrices moving in either direction.

I have limited the drawings forming part of this specification to those parts which are 45 necessary to a proper understanding of my invention. In all other respects the machine may be constructed in accordance with the patent above named or in any other suitable manner.

50 The elevator herein shown corresponds in

general construction and mode of operation to the part N in Patent No. 436,532, and the pawls herein shown are intended as substitutes for the pawls marked n^{20} in said patent.

Figure 1 is a front elevation of such portions of a linotype-machine as are necessary to illustrate the application of my invention, the same having my invention embodied therein. Fig. 2 is a side elevation of the elevator provided with my improved pawls. 60 Fig. 3 is a top plan view of the same with portions broken away on the line 2 2 of the preceding figure in order to expose the pawls to view. Fig. 4 is a vertical cross-section on the correspondingly-numbered line. Fig. 5 illustrates in side elevation and in top plan view one of my dogs or pawls. Figs. 6 and 7 are horizontal sections on the same level as Fig. 3, showing, respectively, the action of the outgoing and incoming matrices. 70

The elevator N consists simply of a horizontal block or head having a vertical slot or opening therethrough from its right end inward a sufficient distance to receive a composed line of matrices. This elevator is 75 grooved internally to receive the shoulders of the matrices and give them support and is in all respects of ordinary construction, except as to the dogs or pawls O¹⁰, forming the subject of the present invention. 80

In the operation of the machine the line of matrices enters the elevator moving toward the left, as shown in Fig. 6, and as the final operation leave the elevator, moving to the right, as shown in Fig. 7. I dispense with 85 the ordinary dogs or pawls used in the elevator and substitute therefor the two horizontal pawls O¹⁰, located one on each side. These pawls consist each of a piece of spring metal bent at one end, as shown in Fig. 5, to form 90 a projection, beveled or inclined on both sides. They are laid into grooves in the outer sides of the elevator, and their projections extend through openings into the interior. They protrude somewhat beyond the inner vertical 95 walls of the elevator, as shown in the several figures. As the matrix-line enters, as shown in Fig. 6, it acts between and against the ends of the pawls, which yield and move outward, allowing the line to pass between them, 100

- after which they close outside of the line, as shown in Fig. 7, so that the matrices are prevented from sliding out and escaping accidentally. When the matrix-line is to be removed, the pressure applied thereto causes the dogs to yield and spring outward, so that the matrices may escape between them. Thus it will be seen the dogs are opened automatically by the action of the matrices.
- 10 The essentials of my invention reside in the employment of pawls or dogs which, although retaining the matrices under ordinary conditions, will yield whenever the line is forced strongly against them in either direction.

15 What I claim as my invention is—

1. As an improvement in linotype-machines, and in combination with the elevator, matrix-retaining dogs or pawls, beveled in both di-

rections, in order that they may yield before 20 the incoming and the outgoing matrices.

2. As an improvement in the Mergenthaler linotype, the elevator grooved in its side walls, in combination with the externally-applied spring-pawls, having their ends projected through to the interior and beveled in both directions, substantially as described. 25

3. In a linotype-machine, pawls to retain a composed line of matrices, adapted to yield under the action of the line when forced to 30 the right and to the left.

In testimony whereof I hereunto set my hand, this 11th day of March, 1898, in the presence of two attesting witnesses.

JAMES MACKIRDY.
